UNITED STATES PATENT OFFICE.

JOHN T. ATHERTON, OF NEW YORK, N. Y.

CARBURETER.

1,185,273.

Specification of Letters Patent. Patented May 30, 1916.

Application filed August 16, 1912. Serial No. 715,432.

To all whom it may concern:

Be it known that I, JOHN T. ATHERTON, a citizen of the United States, and resident of the borough of Manhattan, in the city, 5 county, and State of New York, have invented a new and useful Improvement in Carbureters, of which the following is a specification.

The object of this invention is to provide 10 certain improvements in the construction, form and arrangement of the several parts of a carbureter whereby a more complete intermixture of the liquid hydrocarbon and air is obtained than heretofore and in which 15 the parts are so arranged that they may be readily assembled.

A further object is to provide means whereby the mixture may be varied without changing the position of the needle 20 valve.

A practical embodiment of my invention is represented in the accompanying drawings, in which—

Figure 1 represents the carbureter in top 25 plan, Fig. 2 is a side elevation, Fig. 3 is a longitudinal vertical central section taken in the plane of the line A—A of Fig. 1, and Fig. 4 is an inverted plan view.

The carbureter comprises a lower casing 30 member 1, which contains the liquid hydrocarbon reservoir 2 and an upper casing member 3 which contains the mixing chamber 4, the air intake 5 and the gas outlet 6. The liquid hydrocarbon or float chamber 2 is 35 provided with the usual float 7 and with the liquid hydrocarbon passage 8 in the extension 9 of the lower casing member.

A horizontally arranged open passage 10 leads from the air intake 5 to the mixing 40 chamber 4. A valved passage 11 also leads from the air intake 5 into the mixing chamber 4. The usual adjustable spring-pressed air valve 12 is provided for normally closing the passage 11, which valve and its 45 spring 13 are removed through the opening closed by the removable cap 14. The screw 15 serves as a means for adjusting the tension of the spring 13.

A tubular member 16 is carried by the upper 50 member 3 of the carbureter casing. The spray nozzle 17 is carried by the extension 9 of the valve member 1 of the casing and it projects upwardly into the tubular member 16 but is spaced from the inner wall of 55 said tubular member 16 so as to form an air inlet passage 19 around the nozzle 17. The

spray nozzle 17 is provided with the usual needle valve 18. The tubular member 16 extending above the top of the spray nozzle forms a carbureting chamber 20 and its top is in alinement with the open horizontal passage 10 leading from the air intake 5 so that the stream of air passing through the passage 10 is directed across the top of the said tubular member. A damper 21 is 60 provided for the outlet of the carbureter and where desired an auxiliary damper 22 may be provided for the intake 5. The exterior arms 23, 24, of these two dampers 21, 22, are connected by an adjustable rod 25 70 so that the desired relative opening and closing of the two dampers 21 and 22 may be obtained. The lower member 1 of the carbureter casing is provided with a liquid hydrocarbon inlet 26 in an extension 27. 75 The float chamber 2 may be provided with the usual drip cock 28.

In operation, a certain amount of air is drawn in through the passage 19 and is intermixed in the carbureting chamber with 80 the liquid hydrocarbon as it issues from the spray nozzle. Under certain conditions, an additional amount of air is added to the mixture as it issues from the carbureting chamber, which additional air passes across 85 the top of the tubular member from the passage 10. Under certain other conditions the suction due to the operation of the motor to which the carbureter is attached, will open the air valve 12 to a greater or lesser 90 extent to permit the addition of still more air to the mixture.

The damper 22 in the air intake 5 serves, when it is used in connection with the damper 21, to regulate the amount of air which 95 passes through the intake into the mixing chamber and may be used to entirely cut off the admission of air from this source, permitting only the admission of air through the passage 19.

In a carbureter constructed and arranged substantially as herein shown and described, the proper mixture of air and liquid hydrocarbon is obtained in a very simple and effective manner and the parts may very read- 105 ily be assembled.

What I claim is:—

A carbureter having a mixing chamber, a vertically arranged liquid hydrocarbon spray nozzle, a tubular member extending above 110 the top of said spray nozzle and projecting into said mixing chamber to form a car-

bureting chamber within the tubular member, an air inlet located upon one side of the tubular member, a gas outlet located upon the opposite side of the tubular member, a horizontally arranged restricted open passage leading from said air inlet into the mixing chamber, and located in position to direct a stream of air in a right line directly across the top of the tubular member into the gas outlet, and a valved passage leading from the said air inlet directly into the

mixing chamber for by-passing a portion of the air from said air inlet.

In testimony, that I claim the foregoing as my invention, I have signed my name in presence of two witnesses, this 14th day of August, 1912.

JOHN T. ATHERTON.
